(57) **CLAIM**

The ornamental design for a golf swing alignment device, as shown and described.

DESCRIPTION

FIG. 1 is a perspective view of a golf swing alignment device showing my new design;

FIG. 2 is a top view thereof;

FIG. 3 is a bottom view thereof;

FIG. 4 is a left side view thereof;

FIG. 5 is a right side view thereof;

FIG. 6 is a front view thereof; and

FIG. 7 is a back view thereof; and,

FIG. 8 is another perspective view of the golf swing alignment device.

The broken line showing of a golf tee is included for the purpose of illustrating and forms no part of the claimed design.
